UNITED STATES PATENT OFFICE

2,442,885

FLASK RETAINER

Albert M. Ashman, Seal Beach, Calif.

Application March 23, 1946, Serial No. 656,695

1 Claim. (Cl. 18—33)

1 The present invention relates to flask retainers of a type which permit a flask to be subjected to pressure, such as hydraulic pressure, and thereafter to hold the flask and any molding material in the flask under pressure.

Primarily, the flask retainer of the present invention is utilized in connection with the forming of dentures and prosthetic devices used in dentistry. By way of example, inlays, crowns, bridges and the like may be made very satisfactorily from plastic material such as Crystolex, which is an acrylic resin. Other materials may be used, such as phenol-formaldehyde resin, as well as mixed acrylic resins and vinyl resin. These plastics are capable of combining natural color effects and translucency with excellent color stability. The acrylic resins have good aging properties in the presence of oral fluids and when exposed to the air, as well as having resistance to warping, lightness in weight and comfort in use, with resistance to bacterial growth.

The device of the present invention facilitates the molding of dentures and prosthetic devices used in dentistry.

An object of the invention is the provision of a flask retainer which is simple of construction, positive in operation, performs the function required of it in an efficient manner and is superior to devices now known to the inventor.

In the drawing:

Fig. 1 is a fragmentary partially sectional elevation of the invention;

Fig. 2 is a fragmentary partially sectional side elevation of the invention;

Fig. 3 is a fragmentary sectional view on the line 3—3 of Fig. 1; and

Fig. 4 is a perspective view of one of the elements of the invention.

Referring now with particularity to the drawing:

The improved flask retainer is designated as an entirety by 1, and the same includes a base 2, formed with a pair of screwthreaded studs 3 and 4 adapted to receive and retain the screw ends of posts 5 and 6, which posts are positioned substantially vertically on the base and spaced apart a desired distance. Each post may be substantially circular in cross section and longitudinally flattened at 7, as illustrated in Fig. 3. A top plate 8 is formed with a transverse enlargement 9, which is either integral with the plate or formed separately therefrom, and which enlargement and plate are transversely bored at 10 and 11 to permit passage therethrough of the said posts 5 and 6. Ends of the enlargement 9 are screwthread-

edly bored as illustrated at 12 and 13 to receive wing-type screws designated generally as 14. Heads 15 are provided for the posts 5 and 6 to limit upward movement of the top plate.

The operation, uses and advantages of the invention are as follows:

At 16 I have provided a flask which is adapted to hold a plaster such as Hydro-cel, a product of the U. S. Gypsum Corporation. This plaster 10 constitutes what may be termed an investment material and is formed around the pattern. This pattern is usually made of wax, and the wax is melted from the mold so that further operation may proceed. It is necessary in the practice that 15 the wax material be entirely removed, and this may be done in the usual way, such as by heat and the use of carbon tetrachloride. The plastic is next prepared, and if an acrylic powder is to be used, the monomeric substance is mixed with 20 the polymer so as to form a puttylike mass which may be forced into the mold cavity. This substance is left extruding beyond the plaster in the flask. The flask is then placed on the base 2 between the posts 5 and 6, as shown in Fig. 1, the 25 top member 8 is brought into contact with the top of the flask and specifically the plastic substance, whereupon a ram 17 of a press, such as a hydraulic press, is brought into engagement with the top of the enlargement 9 and the plastic substance is subjected to pressure. The wing screws 30 have been loosened prior to the application of pressure against the top member, and after the desired pressure has been applied the wing screws are tightened so that the screws engage the flattened longitudinal edge 7 of each post to lock the top against movement. The device as an 35 entirety is then placed in a hot water bath for a suitable length of time to polymerize the plastic and form the molded article.

40 The pressing of the plastic into the mold under pressure and maintaining the said pressure prevents vaporization of the plastic during polymerization, with the result that the molded plastic article is not porous, bubbles are not present and 45 a smooth homogeneous structure results which does not require further polishing. It is perhaps unnecessary to state that the plaster is broken from the plastic to permit access to the molded article.

50 I claim:

1. A flask retainer, including a base, a pair of spaced apart upright posts secured to said base, each post formed with a longitudinally flattened area, a top comprising a flat plate provided with a central enlargement transversely extending be-

tween sides thereof, the said plate and enlargement being formed with a pair of transverse bores to permit passage of the posts therethrough, and screw means adjustably carried at both ends of the enlargement for engagement with the flattened areas of said posts to lock the said top in adjusted position thereto.
